UNITED STATES PATENT OFFICE.

FRANCIS MARION AWALT, OF CHILlicothe, TEXAS.

PLOWSHARE.

No. 902,640.

Specification of Letters Patent.

Patented Nov. 3, 1908.

Application filed February 10, 1908. Serial No. 415,183.

To all whom it may concern:

Be it known that I, FRANCIS M. AWALT, a citizen of the United States, residing at Chillicothe, in the county of Hardeman and

5 State of Texas, have invented certain new and useful Improvements in Plowshares, of which the following is a specification.

This invention relates to plowshares, and more particularly to the point thereof, the 10 object being to provide a reinforced point to reduce wear, and also a self-sharpening point.

In the accompanying drawings Figure 1 is a front elevation showing the invention applied to the share of a shovel plow and Fig. 2 is an edge view thereof. Fig. 3 is a transverse section on the line 3—3, and Fig. 4 is a transverse section on the line 4—4 of Fig. 2.

Referring specifically to the drawings, 5 20 denotes a plow shovel of the usual outline, the lower side edges being sharpened as indicated at 6 and tapering to a point. With the exceptions hereinafter noted the shovel does not differ from the ordinary ones.

25 The point of the shovel is reinforced by increasing the thickness of the adjacent portion of the blade. The sides 7 of the reinforcement coincide with the tapering side edges of the blade and join at the point of the 30 blade to form a substantially vertical cutting edge 8. The upper surface of the reinforcement immediately behind the upper end of the cutting edge 8 is convex as indicated at 9 and said convex portion merges with the main body- 35 portion of the blade. The cross section of the reinforcement immediately adjacent the point is triangular as shown in

Fig. 3, the sides 7 of the reinforcement forming the sides of the triangle and merging with the outer portions of the convex surface 40 9.

Reinforcing the point as herein described gives it a greater amount of metal and enables it to withstand greater wear. It can also be tempered to any degree of hardness, 45 and the shape of the point makes it self-sharpening.

In the drawings the invention is shown in connection with the share of a shovel-plow but it is to be understood that cultivator 50 points, lister shares, sweeps etc., may be similarly constructed, and I do not wish to be limited to the particular form of plow-share illustrated. The amount of reinforcement may be varied to suit the size of the 55 share.

I claim:

A plowshare having its lower side edges tapered to a point, said point being reinforced by thickening it, the sides of the reinforcement coinciding with the tapering side edges of the blade and meeting at the point to form a substantially vertical cutting edge, the upper surface of the reinforcement behind the upper end of said cutting edge being 60 65 convex and merging with the main body- portion of the share.

In testimony whereof I affix my signature, in presence of two witnesses.

FRANCIS MARION AWALT.
